KEYBOARD MECHANISM

Edwin L. Reller, Central Township, St. Louis County, Mo., assignor to David O. Royster, Overland, Mo.

Application October 10, 1932, Serial No. 637,144

15 Claims. (Cl. 197—6.6)

This invention relates generally to keyboard mechanisms, and has more particular reference to a keyboard mechanism adapted especially, though not exclusively for use in connection with name and address printing-plate-making machines.

In the making of name and address printing plates, the trade demands that the typography on the plate be in both upper and lower-case characters as occasion may require. Heretofore, however, so far as I am aware, keyboard mechanisms proposed for use with printing-plate-making machines of the type described have necessitated the use of a separate key for each and every upper and lower-case character, so that, for example, approximately eighty keys, or what is known as a double-keyboard, is required in such machines to provide the requisite selection of dies for making the plate, which is too large a keyboard for speed and facility in the use of such a machine.

My invention has hence for its prime object the provision of a key-board mechanism adapted to operate, for example, an eighty-die plate-making machine, that is to say, a plate-making machine employing all the letters of the alphabet in both capital and small letters, as well as the usual figures and other characters commonly employed in a typewriter, with merely forty keys on the keyboard, a key for a particular letter being readily coupled selectively with either an upper or a lower case die as occasion may require, thus greatly expediting the employment of the plate-making machine for its intended purpose.

My invention has for further objects the provision of a mechanism including a plurality of keys arranged in a keyboard for operation like a typewriting machine for controlling the operation of a normally rotating member, as a register-wheel or the like, for accurately stopping the wheel and for locking the same in selected position; the provision, in such mechanism, of safety devices whereby merely one key may be operated at a time; the provision, in an apparatus of the character described of an arrangement whereby the several groups of mechanisms will operate rapidly and in proper sequence; and in general to improve the construction of keyboard mechanism of the type specified.

And with the above and other objects in view, my invention resides in the novel features of form, construction, arrangement and combinations of parts hereinafter described and pointed out in the claims.

In the accompanying drawings (five sheets),—

Figure 1 is a side elevational view, partly broken away and in section, of a keyboard mechanism of my invention;

Figure 2 is a top-plan view of the machine, portions thereof being broken away and other parts shown in section;

Figure 3 is a fragmentary longitudinal sectional view taken approximately along the line 3—3, Figure 2; the mechanism being shown in association with a rotatory so-called printing-plate impression head;

Figure 4 is a fragmentary transverse sectional view taken approximately along the line 4—4, Figure 3;

Figure 5 is a fragmentary sectional view taken approximately along the line 5—5, Figure 3;

Figure 6 is a fragmentary transverse sectional view taken approximately along the line 6—6, Figure 3; and

Figure 7 is a view of a portion of Figure 3, showing one of the keys manipulated in operative position, portions of the mechanism operable responsive to manipulation of the key being shown and other parts removed.

Referring now more in detail and by reference characters to the drawings, the main frame A of the machine comprises a box-like structure composed of a pair of spaced side-walls 1, 2, connected at their upper margins by an approximately horizontal plate or top-wall 3, the side walls 1, 2, being provided with pads or feet for attachment of the frame to a suitable support, not shown.

Disposed suitably, transversely between the side-walls 1, 2, is a shaft or rod 4, on which is pivotally mounted a spaced series of key-bars designated generally by the reference-character B, suitable washers 5 serving for spacing the bars B on the shaft 4.

The main or shank-portions 6 of the bars B extend forwardly from the shaft 4 in substantially parallel relation to a suitable point, and are then bent or offset more or less toward one another at various angles for disposing the front ends of the bars B in a compact group projecting different distances beyond the frame A, the so-offset portions of the bars B having guiding co-operation with a suitable so-called comb 7, disposed transversely between the side-walls 1, 2, for maintaining the bars B in approximate parallelism. The comb 7 includes a horizontal leg or stop against which the respective bars B are tensionally biased by a spring 8 engaging the forward end of the shank 6 and depending from a suitable angle-shaped member 9 transversely

mounted between the frame-walls 1, 2, as best seen in Figure 2.

The bars B carry at their ends upstanding leg portions, as at 10, of different heights for the different levers B, each leg 10 carrying a key 11, the several keys 11 being arranged in four ascending steps or banks in a manner similar to a typewriter keyboard, as will readily be understood from Figures 2 and 3.

10 At its forward end the shank-portion 6 of each bar B pivotally supports a swingable depending A-shaped so-called coupling frame 12, the opposite legs thereof being provided with opposing terminal stops or shoulders 13, 14, respectively, 15 and the medial portion of the frame 12 being bifurcated by a suitably shaped slot 15, as best seen in Figure 3.

Extending transversely through the slots 15 of the series of frames 12 is a shifter-bar or shaft 16 supported at its ends on and by a pair of arms or cranks 17 in turn depending from a shaft 18 oscillatably supported between the frame side-walls 1, 2. Extending forwardly from each crank 17 is a shifter-arm 19 terminating in an upstanding leg on which is mounted a shifter-key 20, as best seen in Figures 2 and 3. Additional springs 8 engaged between the spring support 9 and the levers 19 serve for biasing the latter upwardly on the comb 7 for normally disposing the shifter-bar 16 in forwardly swung position in the machine, as seen in Figure 3.

Disposed transversely between the walls 1, 2, is a bar or support 21, on which is mounted another comb-member 22, the fingers thereof projecting upwardly between and having guiding co-operation with the respective key-bars B for spacing and aligning the same in the machine. Pivotally mounted on the base-portion of the member 22 is a longitudinal series of so-called stroke-lock 40 dogs 23, each terminating in a rounded or V-shaped nose or end, presented upwardly toward and between respective pairs of the key-bars B, the latter being adapted respectively for descending between a pair of the dogs 23 on operative 45 manipulation of the keys 11, as will presently appear, and best seen in Figure 6.

However, on entry of a particular key-bar B in and between a pair of the adjacent dogs 23, the latter are caused to swingably shift or incline 50 from their vertical centers in opposite directions, each dog 23 being adapted, on such inclination to one side or the other of its vertical center, for impinging and shifting in like direction the next-adjacent dog of the series, the latter dog 55 in turn throwing its neighboring dog in like manner, and so on to the end of the series.

The terminal dog 23 of the series impinges the particular one of a pair of suitable stops or pins 60 24 projecting from the comb-member 22 at the opposite ends of the series, the series of dogs 23 then reclining, one upon the other in close or abutting relation, in opposite directions from the point of entry thereinto of the particular key-bar B, for effectively preventing the entry of any other key-bar B into and between the stroke-lock 65 dogs 23, until the former bar B is raised or removed from engagement with its particular pair of engaged dogs 23, as will be understood from Figure 6.

Upstanding from each key-bar B intermediate the ends of the shank 6 is a lug or stop 25, the series of stop-lugs 25 having co-operative engagement with a latch-bar 26 extending transversely to 75

ward and from the series of stops 25 by means of trunnions 27 rotarily engaging the frame walls 1, 2, as best seen in Figure 6.

Intermediate its ends the latch-bar 26 is provided with a rearwardly extending lip or trip-arm 28, and a spring or tension member 29 is engaged between the arm 28 and the spring-support 9 for biasing the latch-bar 26 normally on the front face of the lugs 25. Each lug 25 is provided with an upwardly presented shoulder 10 as shown, which, when a particular key-bar B is depressed for entering into the series of dogs 23, rides under the lower edge of the bar 26 for latching engagement therewith for retaining the bar B in such depressed or manipulated position pending tripping-oscillation of the bar 26 as will presently more particularly appear, and as shown in dot-dash lines in Figure 7. Disposed transversely between side-walls 1, 2, in suitable vertically spaced relation beneath the shaft 4, is a shaft or rod 30 on which is pivotally mounted a series of successive pairs of forwardly extending so-called stop-levers C, D, the stop-levers C being respectively disposed in substantially vertical registration with a corresponding key-bar B, and the stop-levers D being disposed intermediate the levers C, as best seen in Figures 2 and 6, suitable washers 31 serving for spacing the levers C, D, on the shaft 30, as shown in Figures 2 and 3.

Intermediate their ends the levers C, D, guidingly engage a so-called comb 32 depending from the support member 21, whereby the levers C, D, are maintained in substantial parallelism, the levers C, D, being normally tensionally impinged or biased on the bottom face of the bar 21 by means of suitable springs 33 attached alternately to the opposite margins of a spring-support 34 disposed transversely between the frame walls 1, 2, as best seen in Figure 3.

Each pair of stop-levers C, D, is operatively associated with a particular key-bar B, and for such purpose the pair of levers C, D, are extended forwardly from the shaft 30 for embracing a corresponding coupling-frame 12 of the particular key-bar B. From the end of the lever C a stop-pin 35 projects toward the opposing face of the lever D, and from the lever D a stop-pin 36 projects toward the lever C, the pins 35, 36, being 50 spaced longitudinally of the levers C, D, and disposed in the swingable path of movement of the stops 13, 14, of the coupling-frame 12, as best seen in Figures 2 and 3.

Normally, the coupler 12 is disposed with its 55 stop 13 in registration with the pin 36 of the lever D, the pin 35 of the lever C being then in registration with the slot 15 of the coupler 12, whereby, on manipulation of the key-bar B for depressing the same toward the levers C, D, the 60 coupler 12 will co-operate with the pin 36 for in turn depressing or oscillating the lever D about the shaft 30, as seen in Figure 7, the pin 35 finding clearance from the coupler 12 by entering the slot 15 thereof.

However, by manipulation of the shifter-lever 19, the shifter-bar 16 may be shifted rearwardly for correspondingly swinging the coupler 12 and disposing its stop 14 in registration with the pin 35, so that the key-bar B will then, when depressed, actuate the other lever C, the pin 36 in its turn entering partially into the slot 15 of the coupler 12. Thus, it will be seen the key-bars B, as a group may be selectively coupled with the group of levers D, or alternatively, with the group 75

of levers C, at the option of the person operating the machine, for purposes presently appearing.

Rearwardly inclinably depending from each lever C, or D, as the case may be, is an arm 37 5 provided with a longitudinally spaced pair of pins 38 for working in slots 39 of a slide-member 40 mounted flatwise on the arm 37, the slide 40 carrying at its lower end a striker or stop-block 41, as best seen in Figures 3 and 5.

10 The slide 40 of a respective lever C is provided with a forwardly projecting lug 42 to which is attached the lower end of a spring or tensional member 43 whose upper end is attached as at 44 to the body of the lever C, for normally biasing the stop-block 41 upwardly upon the arm 37. For a similar purpose, the slide 40 of a respective lever D is provided with a lug 45, extending more forwardly than the lug 42, and likewise engaged by the lower end of a spring 43 whose upper end is secured as at 46 to the body of the lever D, as best seen in Figure 3.

E designates a so-called stop-cylinder mounted on, for revolution with, a shaft 47 suitably journaled in and through the frame walls 1, 2. 25 Mounted on the periphery of the cylinder E is a suitable spiral stop-member providing a series of teeth 48 arranged in a helical series about the circumference of the cylinder E, the number of teeth or stops 48 being equal to the combined numbers of levers C, D, and the diametrical plane of each stop 48 being disposed in registration with a corresponding strike-block 41 of a particular lever C or D, as the case may be, and as best seen in Figures 3 and 4.

30 One end of the shaft 47 is extended through the frame-wall 1 and has suitably keyed thereto a gear 49 which meshes with a pinion 50, mounted on the end of an approximately horizontal shaft 51 rotarily, also, projecting through the wall 1. The shaft 51 supports, interiorly the wall 1, a bevel-gear 52, which meshes with a bevel-gear 53 mounted on one end of a drive-shaft 54 rotarily supported in suitable manner from and by the frame-wall 1 for projecting its other end 40 rearwardly from the frame A, where the shaft 54 supports a pulley 55 engaged by a belt 56 for operative connection of the shaft 54 with a suitable prime-mover, as an electric-motor or the like, not shown.

45 The bevel gear 53 also meshes with a bevel pinion 57 mounted on the lower end of a vertical shaft 58 rotarily supported in suitable manner in the machine, the shaft 58 projecting a suitable distance above the top-wall 3 of the frame 50 A, and carrying at its upper end a face-plate 59 provided with a pair of diametrically disposed upstanding pins 60.

55 Freely rotarily mounted on the shaft 58 beneath the face-plate 59 is a spur-pinion 61, carrying a pair of upstanding pins 62 disposed diametrically on the pinion 61 and in quadrature or right-angularly with respect to the pins 60 of the face-plate 59. The pins 62 project loosely upwardly through suitable apertures 63 in the face-plate 59, and suitable springs or tensional-members 64 are connected between each pin 62 and an adjacent pin 60 on the face-plate 59 for effecting a yielding connection between the face-plate 59 and the pinion 61, as best seen in Figures 1 and 2.

60 The spur-pinion 61 meshes with a ring gear 65 suitably supported on a register-wheel or indexing gear F disposed in a suitable recess provided in the top frame-wall 3, the wheel F being preferably mounted on a shaft 66 supported at its

lower end on a stud-pin 67 mounted through the floor of the recess as seen in Figure 3, the upper end of the shaft 66 being supported by any suitable bearing means, not shown.

The wheel F is provided with a circumferential 5 series of wedge-shaped or acuminate indexing-teeth 68, equal in number to the series of stops 48 on the cylinder E, the several gears and pinions 49—50, 52—53, 53—57, and 61—65, being of such relative dimensions as to effect one revolution of the wheel F for each revolution of the stop-cylinder E.

10 A head 69, having an acuminate or wedge-shaped point 70 presented toward the teeth 68 of the wheel F, is disposed for suitable movement in 15 a suitable aperture 71 provided in the frame top-wall 3. A suitable bracket 72 depends from the wall 3 and has a way 73 in which the head 69 is guidingly mounted for engagement of its wedge-point 70 with and between a particular 20 pair of teeth 68 on movement of the head 69 toward the wheel F, the head 69 being mounted on one or the upstanding arm of a bell crank lever 74 rockably mounted on a shaft 75 supported in suitable bearings 76 depending from the 25 frame top-wall 3, as best seen in Figure 3.

The other or horizontal arm of the bell-crank 14 is engaged, as at 77, by the lower end of a spring or resilient link-connection 78, the upper end thereof being attached to the end of a crank 30 79 mounted on a rockable-shaft 80 disposed transversely of and between the frame walls 1, 2, as best seen in Figures 2, 3 and 6.

35 Adjacent the respective frame-walls 1, 2, the shaft 80 carries a crank 81 pivotally engaging 35 the upper end of a vertical link 82, as seen in Figure 6, the lower ends of the links 82 pivotally engaging cranks 83 mounted on a shaft 84 disposed transversely in and between the frame-walls 1, 2, the cranks 83 each being extended 40 rearwardly as by arms 85. Supported by and between the swingable ends of the crank-arms 85 is a shaft or trip bar 86 disposed transversely of and subjacent to the series of striker-blocks 41 of the levers C, D, as best seen in Figures 2 and 3.

45 As has been said, manipulation or depression of a particular key-bar B will effect swingable movement of the corresponding lever C, or D, according to the position of the frame 12, responsive to manipulation, if any, of the shifter-rod 16. Thus, as best seen in Figure 7, manipulation of a particular key-bar B will swingably depress the correspondingly associated lever D, for example, causing its carried stop-block 41 55 to be advanced toward the cylinder E for disposition or projection into the path of the cylinder-carried stop 48 aligned with that particular lever D.

50 It follows, therefore, that rotation of the cylinder E will effect engagement of the particular stop 48 with the so-projected block 41, and, since the cylinder E is continuously under rotatory bias imparted by the belt 56 to the pulley 55, the stop 48 will, on impinging the block 41, 65 shift the latter downwardly from the lever-arm 37 against the bias of the spring 43, the tension of the spring 43 meanwhile acting, in some degree, for retarding the rotatory movement of the cylinder E.

70 The cylinder E is brought to a positive stop, however, on impingement of the so-shifted block 41 with a stop-bar 87 fixed transversely between the frame walls 1, 2, the bar 87, I might here state, being provided with a pair of upstanding 75

wings 88 adapted for slidably engaging the opposite end blocks 41 of the bank of levers C, D, for retaining the same in proper alignment with the cylinder E.

5 In order to prevent a shock to the mechanism on stoppage of the cylinder E, I prefer to provide a suitable form of cylinder-brake comprising in the present instance, a pair of brake-drums 89 each mounted on a respective end of the cylinder E, as seen in Figure 4, each drum 89 being interiorly equipped with a pair of opposing arcuate brake-shoes 90, suitably anchored as at 91 to the respective side-walls 1, 2, of the frame A. At its free end, each shoe 90 terminates in a lug 92, the opposing lugs 92 being normally biased one toward the other in brake-released manner by means of a spring or tensional member 93 mounted on a suitable retaining member or bolt 94 passed through the lugs 92, as best seen in Figure 1.

10 Disposed between the lugs 92 and rotarily mounted on a suitable pin 95 projecting from the frame wall 1, or 2, as the case may be, is a rotary cam 96 from which forwardly projects a 15 suitably curved lever 97. A rod 98 is supported by and between the free ends of the levers 97 for disposition in the path of movement of the swingable depending portions of the levers C, D, as best seen in Figure 3, whereby, on manipulative actuation of any one of said levers, the cam 20 96 will be revolved for spreading the lugs 92 apart and for more or less frictionally engaging the shoes 90 with the drums 89, thus effectively retarding the rotary motion of the cylinder E.

25 The cylinder E being brought to rest, the pulley 55 likewise comes to a standstill and the belt 56, slipping frictionally on the pulley 55, acts 30 for holding the cylinder E in stopped position against the tension of the spring 43.

35 It may here be said that, normally, the springs 40 64 act for biasing the pins 62 upon the wall of the respective apertures 63 in the face-plate 59 so that the rotary bias of the belt 56 on the pulley 55 is transmitted directly from the face-plate 59 through the pins 62 to the pinion 61 45 for rotating the wheel F in synchronism with the cylinder E. However, when the cylinder E comes to rest, the springs 64 yield for allowing the pins 62 to shift in the apertures 63, thereby 50 substantially effecting an absorption of the shock of retardation of movement of the wheel F and any apparatus that may be attached thereto.

55 The stop-bar 87 is located in such position in the frame A that, when movement of the cylinder E is arrested by impingement of a particular block 41 with the bar 87, the notch between a corresponding or related particular pair of teeth 68 of the wheel F will be disposed in registration with the wedge 70 of the head 69, as best seen 60 in Figure 2.

65 During the movement of the block 41 toward and upon the stop-bar 87, the rod 86 is impinged by the block 41 and shifted downwardly for, in turn, oscillating the shaft 80, in clockwise direction, reference being made to Figure 3, for movement of the crank 79 in upward direction, and in turn effecting movement of the head 69 toward the wheel F for entrance of the wedge 70 into and between the particular pair of teeth 68 70 of the wheel F that may at the moment be positioned in registration with the head 69, whereby the wheel F is accurately "centered" or disposed in particular, predetermined, position with respect to the axis of the machine.

75 Projecting from the shaft 80 is an arm 99

which carries a screw or other like trip member 100 adjustably mounted in and through the arm 99 for depending therefrom in registration with the lip 28 of the latch-bar 26, the trip-member 100 being disposed for engagement with the lip 28 on clockwise or wheel-centering oscillation of the shaft 80 for tilting or swinging the latch-bar 26 from the lugs 25, that is, from the position shown by dot-dash lines in Figure 7 to that shown by solid lines in the same figure, for releasing or unlatching the particular key B which at the particular moment is retained in depressed position by the latch-bar 26.

80 The particular key B, being thus released from constraint of the latch-bar 26, is by its spring 8 15 drawn or retracted upwardly to normal position, for, in turn, releasing the particular associated lever, as D in Figure 7, the spring 33 of the latter then drawing the lever D upwardly and swinging the block 41 away from the cylinder E, the block 20 41, on disengagement thereof from the particular stop 48 of the cylinder E then being drawn also upwardly to normal position by its spring 43.

85 Projecting forwardly from each link 82 is a lug or stop 110 for engaging the upper face of the 25 spring support 34, a spring or tensional member 110' being engaged between the end of the crank 81 and the spring-support 34 for normally biasing the stop 110 toward the member 34, whereby, on retraction of the block 41 on the lever C, or D, 30 as the case may be, the rod 86 is moved upwardly, the link 82 is moved downwardly until the stop 110 engages the member 34, the shaft 80 is reversely oscillated to its former or initial position, and the wedge 70 is withdrawn from the wheel 35 F, the belt 56 being then again effective for rotation of the cylinders E and wheel F until such time as another key-bar B is depressed, when the foregoing operations are repeated.

90 G designates a practical example of a normally rotating mechanism, comprising, in the present instance, a so-called printing-plate impression device composed of an upper head or drum 101 carrying a series of circumferentially arranged reciprocable punches 102, and a lower head or 45 drum 103 carrying a corresponding series of circumferentially arranged reciprocable dies 104 each in vertical registration with a respective punch 102, the numbers of pairs of members 102, 104, being equal to the number of teeth 68 of the 50 wheel F.

95 G designates a work-support on which the work 106, as a printing-plate or the like, is mounted, the support 105 having an aperture 105' defining a station, as may be said, to which a 55 particular pair of punch and die members 102, 104, is to be selectively brought or positioned, suitable strikers or plungers 102', 104', engageable respectively with the punch 102 and die 104, being operable, by means not shown, for moving the 60 punch and the die one toward the other for engaging the work for forming the selected typographical or other desired impression in the plate 106, the mechanism G being provided also with a suitable feeder 107 actuatable, by means not 65 shown, for shifting the work 106 one space or stop at a time in proper sequence with the operation of the machine, as well known to those skilled in the art and readily understood from Figures 3 70 and 6.

75 Mounted on the shaft 80 is a crank 108 to the swingable end of which is connected a link or plunger 109, having suitable connection, by means not shown, with the mechanism G, of which it suffices here merely to say that, when the shaft 75

80 is oscillated in clockwise direction, reference being made to Figures 3 and 7, the plunger 109 is shifted upwardly for effecting actuation of both the strikers 102', 104', and the feeder 107, for imprinting a character on the work 106 and feeding the same one step or space on the work-support 105.

If desired, a dash-pot or other suitable time-delay device may be incorporated in the mechanism, although, in the present instance, the plunger 109, it may here be said, acts for preventing movement of the shaft 80 under bias of the spring 110', until the impression-making operation is completed; in practice, the interval of delay thus provided for is of very small duration.

A plunger 111 is reciprocably mounted in and through the frame-top wall 3, and is biased as by a suitably mounted spring or tensional member 111', for movement normally in downward direction, the plunger 111 having a collar 111" engageable with the upper face of the wall 3 for limiting the downward movement of the plunger therein. The lower end of the plunger 111 is pivotally engaged with a crank 112 projecting from a shaft 113 mounted transversely between the frame walls 1, 2, the shaft 113 carrying a pair of forwardly extending arms 114 for supporting a so-called space-bar 115 disposed transversely and forwardly of the bank of key-bars B, as clearly seen in Figures 2 and 3.

The plunger 111 is suitably connected by means not shown, with the mechanism G whereby, on depression of the spacer-bar 115, the plunger 111 is operated for effecting actuation of the feeder 107 for moving the work 106 one space on the support 105, no impression, however, being made on the plate or work 106, for providing a space in the typographical matter being impressed on the work.

40 In the use and operation of my invention, and having particular reference, as an example, to the mechanism G, as shown in the drawings, it will be observed that there are forty of the key-bars B, that is to say, the keyboard has merely 45 a single key for each respective letter of the alphabet, and fourteen keys for the other usual typographical characters corresponding to the conventional typewriter keyboard. Likewise, there are forty of the levers C and forty of the 50 levers D, the levers C corresponding to "upper-case" characters, and the levers D corresponding to "lower-case" characters of the keyboard members B. Similarly, there are eighty stops 48 on the cylinder E, and, correspondingly, eighty teeth 55 68 on the register-wheel F. Finally, there are eighty pairs of punch and die-members 102, 104, of the mechanism G, each pair of opposingly movable members 102, 104, comprising a "die" as may be said, the "dies" being mounted in the die-head structure 101, 103, in a series of pairs of 60 "dies" carrying characters of the alphabet, one die of each pair carrying a lower-case character and the other die of the pair carrying an upper-case character of a particular letter of the alphabet.

The foregoing several members and elements are so related and arranged that each key 11 is effective for controlling the operation of both the upper and lower case dies of a particular letter of the alphabet, the keys 11 being normally coupled to the levers D, whereby, on depressing a particular key 11, normally a "lower-case" character will be impressed on the work 106. However, by manipulating the "shifter" key 20, the keys 11 may be coupled to the levers C, whereby, on depressing

a particular key 11, an "upper-case" character will be imprinted on the work 106. Likewise, by manipulating the "spacer" bar 115, a space will be provided on the work 106 between the characters imprinted thereon.

It will then be seen that my invention accomplishes its objects, and provides a keyboard mechanism for use especially though not exclusively, in connection with a printing-plate-making machine having a die-head containing a series of 10 dies carrying characters including capital and small letters of the alphabet, and a keyboard wherein one key in the keyboard will selectively actuate both the capital and small letter dies of a particular letter of the alphabet.

However, I do not wish to be limited in the use of my invention to the particular embodiment of mechanism G as shown, but may employ my improved keyboard mechanism also for any purpose where a normally rotating member, for example, 20 is to be selectively stopped, my invention providing in such case a keyboard and means responsive to actuation of the keyboard for stopping said member in selected position.

It will be understood that changes and modifications in the form, construction, arrangement, and combination of parts of my improved keyboard mechanism may be made and substituted for those herein shown and described without departing from the nature and principles of my 30 invention.

Having thus described my invention, what I claim and desire to secure by Letters Patent is.—

1. In a mechanism of the character described, in combination, a rotary member, a stop on the 35 member, a swingable arm for registration with the stop, means for shifting the arm for disposing the same in the path of the stop, means operable for latching the arm in shifted position, and means for unlatching the arm responsive to engagement thereof with the stop.

2. In a mechanism of the character described, in combination, a rotary member, a stop on the member, a swingable arm, an element shiftable for longitudinal movement on the arm, means for 45 shifting the arm for disposing the element in the path of the stop for movement of the element responsively to engagement thereof with the stop, and means for limiting the movement of the element for arresting the rotary motion of said member.

3. In a mechanism of the character described, in combination, a rotary cylinder, stops disposed on the cylinder, a plurality of shiftable arms, an element carried by each arm for registration 55 with a respective stop, a key-member selectively operable for shifting a respective arm for disposing its carried element in the path of the corresponding stop, means for releasably latching the key-member in operated position, and means 60 actuatable responsively to engagement of the element with the stop for releasing the latching-means from the key-member.

4. In a keyboard mechanism for use with a printing-plate-making machine having a die head 65 provided with a series of pairs of movably mounted dies carrying characters of the alphabet and wherein one die of each pair carries a lower-case character and the other die of the pair carries an upper-case character of a particular letter of 70 the alphabet, in combination, a series of key-members each associated with a pair of said dies, and mechanism including a bifurcated frame, and levers selectively actuatable by the bifurcated frame 75 responsive to operation of a particular key-mem-

ber for respectively operating an upper or lower-case die of a corresponding pair thereof.

5. In combination, a key-board having merely a single key for each respective letter of the alphabet, a die-head having merely a single row of individual dies for each respective upper and lower-case character of the letters of the alphabet, mechanism for selectively effecting operation of a particular die, and means including series 5 of bifurcated frames and pairs of levers alternatively cooperable with the respective frames in response to actuation of a particular key for alternatively selecting an upper or lower-case die of the corresponding letter of the alphabet.

15 6. In a mechanism of the character described, in combination, a rotary member, a stop on the member, a swingable arm, an element shiftable on the arm, means for shifting the arm for disposing the element in the path of the stop for 20 movement of the element responsively to engagement thereof with the stop, and braking means including a member actuatable responsively to engagement thereof by the shifted arm for retarding motion of the rotary member.

25 7. In a mechanism of the character described, in combination a rotary cylinder, series of stops on the cylinder, series of shiftable arms, a movable element carried by each arm for registration with a respective stop, a key member selectively operable for shifting a respective arm for disposing its carried element in the path of the corresponding stop, means for releasably latching the key member in operated position, means 30 actuatable responsively to engagement of the element with the stop for releasing the latching means from the key member, and braking means including a member actuatable responsively to engagement thereof by the shifted arm for retarding motion of the cylinder.

40 8. In a mechanism of the character described, in combination, a rotary member, a stop on said member, a swingable arm, an element movable on the arm, means for shifting the arm for disposing the element in the path of the stop, means 45 operable for latching the arm in shifted position, and means for unlatching the arm responsively to movement of the element on engagement thereof with the stop.

9. In a mechanism of the character described, 50 in combination, a rotary member, a stop on said member, a shiftable arm, an element movable on the arm, means for shifting the arm for disposing the element in the path of the stop, means for releasably latching the arm in shifted position, 55 means actuatable responsively to movement of the element on engagement thereof with the stop for unlatching the arm, and braking means including a member engageable by and actuatable responsively to movement of the arm for retarding motion of 60 the rotary member.

10. In a mechanism of the character described, in combination, a rotary member, a stop on said member, a shiftable arm, an element movable on the arm, means for shifting the arm for disposing 65 the element in the path of the stop, means for releasably latching the arm in shifted position, means actuatable responsively to movement of the element on engagement thereof with the stop for unlatching the arm, braking means including a 70 member engageable by and actuatable responsively to movement of the arm for retarding motion of the rotary member, and means for limiting the movement of the element.

11. In combination, a key-board having merely 75 a single key for each respective letter of the al-

phabet, a die-head having merely a single row of individual dies for each respective upper and lower case character of the letters of the alphabet, mechanism for selectively effecting operation of a particular die, means including series of bifurcated frames and pairs of levers alternatively actuatable by the respective frames in response to actuation of a particular key for alternatively selecting an upper or lower case die of the corresponding letter of the alphabet, means for latching a selected lever in actuated position, and means for unlatching the lever responsively to actuation of the die-operating mechanism.

12. In a mechanism of the character described, in combination, a rotary die-head, series of dies 15 carried by the head, a register wheel having pairs of teeth each corresponding to a die in the head, an element engageable with said wheel, a rotary cylinder having series of stops each corresponding to a pair of said teeth, means for actuating the die-head, the wheel and the cylinder in unison, means including a member shiftable for engagement with a particular stop of the cylinder for arresting the motion thereof for stopping the head and the wheel in predetermined position, 25 means for latching said member in shifted position, and means operable responsively to engagement of said member with the stop for concurrently engaging said element with a corresponding pair of the teeth of the wheel and releasing 30 said member from the latching means.

13. In a mechanism of the character described, in combination, a frame including a work-support, a rotary diehead, a series of dies carried by the head, a register-wheel having pairs of teeth each pair of teeth corresponding to a respective die in the head, an element engageable with said wheel, a rotary cylinder having a series of stops each stop corresponding to a pair of said teeth, 35 means for actuating the die-head, the wheel, and the cylinder in unison, means including a member shiftable for engagement with a particular stop of the cylinder for arresting the motion thereof for stopping the head and the wheel in predetermined position in the frame, means for 40 latching said member in shifted position, means responsive to shifting movement of said member for retarding motion of the cylinder, and means operable responsively to engagement of said member with the stop for, concurrently engaging said 45 element with a corresponding pair of the teeth of the wheel for temporarily retaining the die-head in registration with the work-support, and releasing said member from the latching means for in turn releasing the cylinder from the retarding 50 means.

14. In a mechanism of the character described, in combination, a frame including a work-support, a rotary die-head, a series of dies carried by the head, a register-wheel having pairs of teeth each pair of teeth corresponding to a respective die in the head, a rotary cylinder having a series of stops each corresponding to a pair of said teeth, means for actuating the die-head, the wheel, and the cylinder in unison, a plurality of elements respectively movable toward the cylinder for engaging a corresponding stop thereof, means for supporting said elements for shiftable movement responsive to engagement thereof with the stop on the cylinder, means for limiting the movement of said element for arresting the motion of the cylinder for stopping the head and the wheel in predetermined position in the frame, means responsive to movement of any of said elements and including 70 a member engageable with a corresponding pair 75

of the teeth of the wheel for temporarily retaining the die-head in registration with the work-support, and means responsive to movement of an element toward the cylinder for retarding the motion of the cylinder.

5 15. In a mechanism of the character described, in combination, a frame including a work-support, a rotary die-head, a series of dies carried by the head, a register-wheel having pairs of teeth each 10 pair of teeth corresponding to a respective die in the head, a rotary cylinder having a series of stops each corresponding to a pair of said teeth, means for actuating the die-head, the wheel and the cylinder in unison, a series of members respectively 15 actuatable for disposition in the path of a

corresponding stop on the cylinder, means for latching a member in actuated position, means for arresting the motion of the cylinder responsive to engagement of a member with a corresponding stop for stopping the head and the 5 wheel in predetermined position in the frame, an element for engaging the wheel in stopped position, and means also responsive to engagement of a member with its stop for concurrently releasing said member from the latching means and 10 engaging said element with a corresponding pair of the teeth of the wheel for retaining the die-head in stopped position.

EDWIN L. RELLER. 15
